Primary Examiner—Martie K. Holtje*Attorney, Agent, or Firm*—Knobbe, Martens, Olson & Bear, LLP[57] **CLAIM**

The ornamental design for a zippered binder pocket, as shown and described.

DESCRIPTION

FIG. 1 is a front elevational view of a zippered binder pocket showing my new design;

FIG. 2 is a rear elevational view;

FIG. 3 is a right side elevational view;

FIG. 4 is a left side elevational view;

FIG. 5 is a bottom plan view;

FIG. 6 is a top plan view;

FIG. 7 is a front elevational view of a second embodiment of my new design;

FIG. 8 is a front elevational view of a third embodiment of my new design; and,

FIG. 9 is a front elevational view of a fourth embodiment of my new design.

FIGS. 2 through 6 are representative of the rear, right and left sides, and bottom and top views in the embodiments of FIGS. 7, 8 and 9.
